UNITED STATES PATENT OFFICE.

WILLIS E. BARBER, OF LA CROSSE, WISCONSIN.

TOWEL-HOLDER.

1,116,209.

Specification of Letters Patent.

Patented Nov. 3, 1914.

Application filed October 22, 1912. Serial No. 727,265.

To all whom it may concern:

Be it known that I, WILLIS E. BARBER, citizen of the United States, residing at La Crosse, in the county of La Crosse and State 5 of Wisconsin, have invented certain new and useful Improvements in Towel-Holders, of which the following is a specification.

My invention relates to new and useful improvements in towel holders and has for 10 one of its objects the provision of a towel holder which will support a plurality of towels.

Many hotels and other public places now supply individual towels for guests which 15 are commonly supported in piles upon a shelf or table and which, when used, are usually deposited in a hamper which is emptied from time to time. Towels when merely laid upon a shelf in the manner 20 above described are apt to be displaced and to fall upon the floor and the towels when used may be deposited in the hamper which is supplied for that purpose or may be left 25 lying about the room or thrown upon the floor. Furthermore, the towels being free, the guests may remove the same from the room. For the above reasons the various 30 methods now in use for supplying towels to guests in public places have been found to be unsatisfactory.

A further object of my invention is therefore to provide a towel holder which will support a plurality of clean towels in superimposed relation upon a shelf and which 35 will prevent them from falling to the floor if accidentally displaced from the shelf.

A further object of my invention is to provide a support for the clean towels and a hanger for holding the soiled towels after 40 use, and in order that the towels may not become scattered about the room I further provide a transfer device operatively connecting the support and hanger in such a manner that the towel is never free from the 45 holder proper.

A further object of my invention is to so construct and arrange the support, transfer device and hanger that they will in no way interfere with the employment of the 50 towel in the ordinary manner and in such a manner that the guest, after using the towel, need only drop the same when the towel will automatically pass to the hanger.

A further object of my invention is to 55 so construct the towel holder that fresh towels may be readily positioned thereon

and soiled towels removed therefrom. And a still further object of my invention is to provide means for locking the towels upon the holder so as to prevent their being removed from the room.

With these and other objects in view, my invention will be more fully described, illustrated in the accompanying drawings, and then specifically pointed out in the claims 65 which are attached to and form a part of this application.

In the drawings: Figure 1 is a perspective view of my improved towel holder in operation; Fig. 2 is a vertical sectional view, 70 showing such details of construction as are not clearly brought out in Fig. 1; Fig. 3 is a perspective view of a double form of towel holder, this figure also illustrating a slightly modified form of construction; Fig. 4 is a 75 fragmentary view of one of the towels employed with this holder, showing a loop attached to the corner to permit the stringing of the towels upon the holder; Fig. 5 is a similar view, showing another way of 80 adapting the towels for use in connection with my holder.

Corresponding and like parts are referred to in the following description and indicated in all the views of the drawings by the 85 same reference characters.

My invention preferably includes a supporting shelf 10 and backboard 11 rigidly connected to each other and suitably braced by brackets 12. A supporting standard 13 90 is preferably secured by its upper end to the backboard 11 and extends by its lower end a considerable distance below the same. In order to permit the positioning of the towel holder against a wall or other suitable support, the rear face of the backboard 11 is preferably recessed in such a manner that the upper end of the standard 13 lies flush with the backboard, as shown by dotted lines in Fig. 2 of the drawings.

That portion of the holder above described may be secured against a wall or support by suitable fastening devices, such as screws, passed through the backboard and supporting standard or it may be supported above the wash bowls by the supporting standard 13 alone.

The shelf 10 preferably conforms in shape and size to the towels which it is to support but may be made smaller than the towels if 110 the latter are to be folded before placing them thereon. Secured to the lower face of

the shelf 10 and adjacent one of its forward corners, is a plate 14 carrying a tubular supporting spindle 15 which extends through a bore formed in the shelf and to any desired height above the shelf. This spindle should however, extend as high above the shelf as the towels are to be piled in order to simplify the positioning of the towels upon the holder.

10 The clean towels which are conventionally shown at 16 are strung upon the spindle 15 either by means of a loop 17 attached to one corner of the towel and passed over the spindle, or by means of eyelet holes 18 formed in one corner of the towels. When so mounted upon the shelf, it will be apparent that the brackets 12, together with the spindle will tend to prevent the accidental displacement of the towels from the shelf, 15 and that even though brushed from the shelf, the towels will still be supported by the spindle.

In order to prevent the free removal of the towels from the holder and in order to supply a hanger for supporting the soiled towels, I provide a transfer device 19 comprising a rod, preferably of resilient metal, bent into the shape of a U and with one side portion telescopically mounted in the upper 25 end of the tubular spindle 15, as shown at 20. This U-shaped transfer member is so proportioned that its free side extends beyond the outer line of the shelf and below the shelf and this free end is bent inwardly 30 and downwardly to form a hanger 21, the free end 22 of which is passed through a sleeve 23 carried by a plate 24 mounted upon the lower end of the supporting standard and is adjustably secured in place by means 35 of a set screw 25 threaded through the sleeve and engaging against the end 22 of the hanger.

If desired, the intermediate portion of the hanger may be extended downwardly 45 and then upwardly before being passed through the sleeve 24 to form a loop 26 from which the soiled towels will hang as shown in Fig. 1 of the drawings.

In operation, the clean towels are threaded 50 upon the spindle 15 and supported upon the shelf 10. The shorter arm of the transfer member is then positioned in the spindle and the free end of the hanger member is passed through the sleeve 23 and locked in 55 place.

It will be apparent from the foregoing description that it will be absolutely impossible to completely remove the towels from the towel holder without first loosening the 60 set screw 23 and removing the free end of the hanger from its sleeve.

In use, the towels are successively removed from the pile by the guests, the towel in each case being raised up over the right 65 portion of the transfer member, employed in

the customary manner and then released. Upon its release, it falls by gravity upon the hanger 21 and is supported by the hanger above the floor. When fresh towels are to be supplied or soiled towels are to be removed from the hanger, the set screw 23 is released and the combined transfer device and hanger raised a sufficient distance to free the end 22 when the soiled towels may be slipped over said end into a suitable 75 hamper and carried away.

It will of course be understood that any number of spindles, transfer devices and hangers may be employed with a single shelf and for the sake of clearness, I have 80 illustrated the employment of two supporting devices in connection with a single shelf in Fig. 3 of the drawings. In this figure, the supporting device shown at the left is identical with that above described, while 85 that shown at the right differs somewhat in that the hanger there designated by the numeral 27 is merely a straight continuation of the longer side of the transfer device being passed directly downward through the 90 sleeve without any formation of a loop such as that shown at 26 in Fig. 1 of the drawings. Another point of difference to be noted in this hanger is the method in which the free end of the hanger is secured in its 95 sleeve, this being accomplished by means of any suitable form of lock 28 which absolutely prevents the removal of towels from the support by other than employees.

The towels shown at the left of Fig. 3 are 100 similar to those shown in Figs. 1 and 4, while the towels at the right are constructed in accordance with the showing of Fig. 5 of the drawings, being provided with eyelet holes for threaded engagement upon 105 the spindle rather than with the loops.

Although I have illustrated both hangers as secured in sleeves carried by a single plate 29 in Fig. 3 of the drawings, it will of course be understood that a separate plate 110 may be employed for each hanger. It will further be understood that when the towel holder is to be secured against a wall, the backboard and supporting standard may be omitted, if desired, in which case, the sleeve 115 carrying plate or plates will be secured directly to the wall.

From the foregoing description, it will be apparent that I have provided an extremely simple and efficient form of towel holder 120 and one adapted to support a plurality of towels for individual use, in such a manner that the clean and soiled towels are kept separate and in such a manner that the employment of the towels in the ordinary 125 manner is in no way interfered with.

Having thus described the invention, what is claimed as new is:

1. A towel holder including a supporting shelf, a tubular spindle extending upwardly 130

- from said shelf, a plate positioned below the shelf, a locking device carried by said plate, and a rod having one end telescopically mounted in the upper end of the spindle, the 5 free end of the rod being bent upwardly and downwardly and detachably secured in the locking device.
2. A towel holder including a supporting shelf, a tubular spindle extending upwardly 10 from said shelf, a plate positioned below the shelf, a locking device carried by said plate, and a rod having one end telescopically mounted in the upper end of the spindle, the free end of the rod being bent upwardly and 15 downwardly and detachably secured in the locking device, said downwardly directed portion being provided intermediate its length with a towel retaining loop.
3. A towel holder including a supporting shelf, a tubular spindle extending upwardly 20 from the shelf, a plate positioned below the shelf, a locking device carried by the plate, a rod having one end detachably seated in the upper end of the tubular spindle, said rod being bent outwardly and downwardly 25 to a point adjacent the locking plate then inwardly and upwardly and having its free terminal rebent to extend downwardly into the locking device, and means for securing said terminal in the locking device. 30

In testimony whereof I affix my signature in presence of two witnesses.

WILLIS E. BARBER. [L.S.]
